UNITED STATES PATENT OFFICE

CALVIN V. DAVIS, OF MOUNT VERNON, NEW YORK, ASSIGNOR TO AMBURSEN CONSTRUCTION COMPANY, INC., OF NEW YORK, N. Y., A CORPORATION OF NEW YORK

DAM

Application filed April 30, 1930. Serial No. 448,534.

This invention relates to a novel and improved type of dam, and more particularly to a foundation structure adapted for use where the foundation material contains areas which are unsuitable for supporting the load of the dam. The invention will be best understood from the following description and the annexed drawings, in which I have shown selected embodiments of the invention and in which:

Fig. 1 is a vertical sectional view extending up- and down-stream through a dam constructed according to the invention.

Fig. 2 is a view on an enlarged scale, taken approximately on the line 2—2 of Fig. 1 and showing one embodiment of the invention.

Fig. 3 is a view corresponding to Fig. 2, but showing a different form of the invention.

At certain sites selected for the construction of dams there is frequently found an area or areas comprising foundation material not capable of taking the full loading put upon it by the dam structure. Such areas

frequently occur at portions of a site which is otherwise of excellent material for dam construction. Examples of such areas are furnished by rock, which is different in character from the high-grade rock adjacent it or rock which may be broken or have lines

of cleavage not capable of resisting the sliding forces put upon it by the weight of the structure; a faulted condition caused by earthquakes or major earth movements; or a deep narrow gorge filled with earth or other soft material which it would be uneconomical to excavate.

An example of a situation which may be found is shown in Figs. 2 and 3, wherein A designates a portion of soft material which may be found in the stream bed across which the dam is being built and which may extend downwardly for a great depth. Adjacent this material may be found a portion B of broken rock capable of taking more load than

the portion A but still not sufficiently good to support the dam structure. On opposite sides of the poor material A and B it is not uncommon to find sound rock areas C.

According to prior art practice, it has been the custom to bridge a fault such as that described above, by means of a reinforced beam or slab upon which the superstructure of the dam is placed. With such a construction, however, when the load is applied to the slab or beam, there is apt to occur a differential in settlement because of the difference in character of the foundation material beneath the slab.

According to this invention, I construct the buttresses 1 in much the usual way, carrying to solid rock those that can be so carried with economy, but resting those above the material A and B upon a footing 3. This footing is in the form of a slab capable of transmitting to the material A and B that portion of the buttress loading which this material will carry without undue settlement. Extending between the buttresses which are above the material A and B and spanning that material is a plurality of transversely extending ribs 4, these ribs extending from the slab or footing 3 upwardly between the buttresses, and being spaced apart up- and downstream, as plainly shown in Fig. 1.

In Fig. 2, the top surface 5 of each of these ribs is formed as the extrados of an arch which is composed of the upper portion of the rib, the theoretical intrados being indicated by the line 6. The ribs extend completely across the faulty material A and B and rest securely upon the sound rock C on opposite sides of the fault, where suitable abutments may be had. Preferably, the footing or slab 3 is integrally connected with the ribs near their ends, so that this slab forms, at the webs, chords connecting the haunches of the arches adjacent their abutments. The arch is shown as provided with reinforcement 7 adjacent the intrados and the

extrados, but this may be omitted if desired. The structure also may be so designed that upon loading of the arches, joints 8 between the ribs and the buttresses may open. By proper designing, this opening of joints may be restricted to points beneath the intrados 6 and above the extrados 5 of each arch. As the load is taken off the arches, the joints 8 may close again or, under certain conditions, they may remain open, but in any case the structure can be so designed that there should be no forming of cracks in the theoretical arch. The portion of each web disposed between two adjacent buttresses is integral with the theoretical arch, but may or may not be integral with the adjacent buttresses. In either case, the principle of the internal arch is used in designing each web.

Referring now to Fig. 3, I have shown therein a construction adapted to resist side thrust which may be caused for example, by sidewise pressure of the material above the fault D. This sidewise pressure may be and usually is increased by pressure from the weight of the superstructure resting thereon.

In order to resist this pressure, I build the ribs, in this form, to such a height as to brace the buttresses against the pressure exerted by the side thrust. The ribs 9, in this form, are shown as having substantially horizontal tops 10 and, here again, the principle of the internal arch is relied upon to form a supporting structure spanning the faulty material A and B, and adapted to support the buttresses which would ordinarily rest upon this faulty material. In this form also, reinforcing may be used in the theoretical arch, the extrados and intrados of which are indicated respectively at 5' and 6', although reinforcing is not shown in this figure. Similarly, the ribs may be built integrally with the buttresses, or joints 8 may be provided as in the form shown in Fig. 2.

In both Figs. 2 and 3, it will be seen that the ribs form a substantially continuous arch over the faulty material A and B, even though the form of the rib may not be that of an arch.

It is of course understood that, in this type of dam, the buttresses 1 are employed to support an up-stream deck 11 which comes in contact with the water in the reservoir and which transmits the load through the buttresses to the foundation. In order to prevent the building up of unequal pressure caused by the percolation of back water through the dam, I provide drains 12 through the ribs 4, and other drains 13 extending through the slab 3.

The above construction not only provides an arch support or supports for the buttresses across a fault, but it also provides a cellular construction consisting of a plurality of adjacent cells which may be tied together as

found desirable, and which thus forms a strong foundation structure.

I claim—

1. A masonry dam comprising an upstream deck supported by a plurality of buttresses, and ribs extending between adjacent buttresses and forming therewith a substantially continuous structure resting at either end on solid bearing material and designed to act as an arch to help support the buttresses and also to resist compressive forces acting lengthwise of the dam. 70

2. A masonry dam comprising an upstream deck supported by a plurality of buttresses, ribs extending between adjacent buttresses and forming therewith a substantially continuous structure resting at either end on solid bearing material and designed to act as an arch to help support the buttresses and also to resist compressive forces acting lengthwise of the dam, and masonry closing the space beneath said arch. 80

3. A masonry dam comprising an upstream deck supported by a plurality of buttresses, ribs extending between adjacent buttresses and forming a substantially continuous structure resting at either end on solid bearing material and designed to act as an arch, the buttresses extending below said arch, and a slab on which the buttresses rest in part. 90

4. A masonry dam comprising an upstream deck supported by a plurality of buttresses, ribs extending between adjacent buttresses and forming a substantially continuous structure resting at either end on solid bearing material and designed to act as an arch, the buttresses extending below said arch, and a slab on which the buttresses rest in part, said slab also forming a chord connecting the haunches of the arches adjacent their abutments. 100

5. A masonry dam comprising an upstream deck supported by a plurality of buttresses, ribs extending between adjacent buttresses and forming a substantially continuous structure resting at either end on solid bearing material and designed to act as an arch, and a chord connecting the haunches of the arch adjacent their abutments. 110

6. A masonry dam comprising an upstream deck supported by a plurality of buttresses, ribs extending between adjacent buttresses and forming a substantially continuous structure resting at either end on solid bearing material and designed to act as an arch, the buttresses extending below said arch, a slab on which the buttresses rest in part, and drains extending through said slab between the buttresses. 120

7. A masonry dam comprising an upstream deck supported by a plurality of buttresses, and ribs extending between adjacent buttresses and forming therewith a substantially continuous structure resting at either end on solid bearing material and designed to act as an arch, the buttresses extending below said arch, a slab on which the buttresses rest in part, and drains extending through said slab between the buttresses. 130

end on solid bearing material and designed to act as an arch, said ribs having portions disposed above the theoretical arch and extending laterally therefrom to transmit side

5 thrust to the arch.

8. A masonry dam comprising an upstream deck supported by a plurality of buttresses, and ribs extending between adjacent buttresses and forming therewith a substantially continuous structure resting at either end on solid bearing material and designed to act as an arch, portions of the ribs extending one side of the theoretical arch, and joints between the buttresses and ribs on said

15 side.
